UNITED STATES PATENT OFFICE.

WILLIAM B. TERRY, OF MARLOW, INDIAN TERRITORY.

OSCILLATING PROPELLER.

SPECIFICATION forming part of Letters Patent No. 747,506, dated December 22, 1903.

Application filed January 31, 1903. Serial No. 141,269. (No model.)

To all whom it may concern:

Be it known that I, WILLIAM B. TERRY, a citizen of the United States, residing at Marlow, Chickasaw Nation, Indian Territory, 5 have invented new and useful Improvements in Oscillating Propellers, of which the following is a specification.

This invention relates to propellers for boats and the like simulating somewhat an 10 oar; and the purpose of the same is to obtain a regular and increased forceful impact of the blades against water and a minimum of resistance on the return stroke, the propeller being completely submerged when in use and 15 automatically opening to catch on the forward stroke and adapted to be actuated either by manual or motive power.

The invention consists in the construction and arrangement of the several parts which 20 will be more fully hereinafter described and claimed.

In the drawings, Figure 1 is a side elevation of a boat, showing the improved propeller applied thereto. Fig. 2 is a rear elevation 25 of one set of the propeller or oar blades, shown open. Fig. 3 is a rear elevation showing the blades closed, or in the position they occupy in relation to each other at the beginning of the forward stroke. Fig. 4 is a horizontal section on the line 4-4 of Fig. 2. Fig. 30 5 is a horizontal section on the line 5-5 of Fig. 2. Fig. 6 shows detached perspective views of the parts of the lock-hinge for the blades.

Similar numerals of reference are employed 35 to indicate corresponding parts in the several views.

The improved propeller is adapted to be used in connection with oar-locks, similar to the ordinary oars, and manually operated or 40 applied to the opposite sides of boats of any dimensions and actuated by steam or electric motors and applicable to either large or small vessels, and in view of the regularity and positiveness of the catch of the blades the 45 full power of the engines or motors will be continuously transmitted to the improved devices, and lost motion, or what is ordinarily termed "run away," of the engines or motors will be obviated. There are numerous modes 50 of arranging the propellers so as to obtain the best speed results with a minimum expenditure of operating power, and various

well-known mechanisms for directly operating the propellers will be adopted to meet various contingencies and constructions resident in boats to which it is desired to apply the improved propeller. It is also proposed to arrange the propellers in series on opposite sides of a boat to have a push-and-pull action and on the return stroke in both instances 60 to reduce the resistance to a minimum, with obvious advantages in speed, as clearly indicated by Fig. 1. The simplified use of the improved propeller, however, will be in the form of a manually-operated construction of 65 oar; but in all uses and applications the blades of the improved device will be held continuously submerged.

The specific description of one of the propellers or oars will apply to all that are used, 70 by reason of the fact that the construction will be duplicated in each, and referring to the parts by numerals the numeral 1 designates a loom, which in the present instance is in the form of a cylindrical bar and will be 75 supplied with a suitable handle or grip when the improved device is employed in the same manner as an ordinary manually-operated oar, or it may be cranked or bent when applied to opposite sides of a motor-driven vessel. The dimensions of this loom will depend upon the proportions of the remaining parts of the improved device and the resistance required commensurate with the operative power. On the outer extremity of the 80 loom is a pair of blades 2, supplied with hinge members 3, engaging the loom, and with an intermediate lock-hinge for limiting the 85 opening and closing movements of the blades. This lock-hinge comprises two members 4 and 90 5, as clearly shown by Fig. 6, each member having a flattened shank 6 firmly secured to the one side of each blade, and both blades at the point of location of the said lock-hinge are formed with slots 7 to provide a clearance for 95 the operation of the members 4 and 5. The inner extremity of the member 4 has a bearing-table 8 in a plane at right angles to the shank thereof, and from the rear side of said table a stop-flange 9 is upstruck. The inner 100 extremity of the member 5 is in the form of a bearing-table 10, which closely contacts and moves on the table 8, and at its rear side edge said table 10 is constructed with a stop-

shoulder 11, which engages with one edge of the upstanding stop-flange 9 and prevents the blades 2 from opening rearwardly beyond a predetermined extent. The front edge of 5 the table 10 adjacent to the shank of the member 5 has a recess 12, so as to give a clearance for the blades to close, the wall of the said recess 12 contacting with a corresponding portion of the opposite member 4 at the point 10 where the shank 6 thereof angularly continues into the table 8, and by this means the blades 2 are always held partially open, as shown by Fig. 5, so that they will reliably catch on the forward stroke of the propeller 15 and be forced open to their full extent as they are resistfully brought against the water, and thereby avoid failure to operate, which might arise if the blades were permitted to come together in close contact. 20 Below the table 8 and above the table 10 nuts 13 are mounted on the loom to prevent the members of the lock-hinge from longitudinally slipping, and by this means the blades are held in one position in relation to the 25 loom and displacement thereof is obviated. When the blades are thrown open by forceful impact against the water, the one edge of the upstanding flange 9 strikes the shoulder 11, and the two blades will then be in the position shown by Fig. 4, the said flange being 30 of a length sufficient to resist fracture or breakage by the continuous sudden impact of the shoulder 11 thereagainst, and a portion of the edge of the table 10 is in the arc 35 of a circle, as at 14, and the flange 9 is correspondingly curved, so that the said edge and flange will move in close relation and an accurate registration or movement of the edge of the flange with the shoulder 11 will at all 40 times result.

The loom 1 also has an auxiliary stop attachment to remove a great portion of the strain from the members of the lock-hinge, the said auxiliary attachment comprising a 45 central collar or sleeve 15, which is securely fastened on the loom immediately below and

close to the lock members and having radial arms 16, which extend over the rear portions or faces of the blades 2 and across the plane of the slot 7 when the blades are open and 50 terminally bear upon portions of the blades beyond the outer terminal walls of the said slots 7.

In the operation of the improved device the blades regularly open and close without the 55 least obstruction and will be exceptionally efficient in propelling a boat either by manual operation or in connection with a motor. The auxiliary stop attachment also prevents the blades from swinging around on the loom 60 and insures their proper presentation at all times to obtain a maximum impact operation in relation to the water.

Having thus fully described the invention, what is claimed as new is— 65

A propeller, comprising a loom having blades movably attached thereto near their outer ends, a lock-hinge consisting of two members secured to the center of the blades and both having the loom extending therethrough, the edge of one member being formed partly in the arc of a circle and having a shoulder on one side, and a recess on its opposite side, and the other member having an upwardly-curved flange to coact with 70 said shoulder to regulate the opening movements of the blades, the shank of the flanged member coacting with the recess in the other member by means of which the blades are always held partially open, and an auxiliary 75 stop comprising a sleeve secured to the loom and approximately near the lock-hinge, said sleeve being provided with oppositely-extending arms which are adapted to bear against said blades, substantially as specified.

In testimony whereof I affix my signature in presence of two witnesses.

WILLIAM B. TERRY.
